UNITED STATES PATENT OFFICE.

ALBERT HENRY AND GILBERT V. B. FRICKE, OF HOBOKEN, NEW JERSEY.

SHOE-PROTECTOR.

1,328,957.

Specification of Letters Patent.

Patented Jan. 27, 1920.

Application filed February 28, 1919. Serial No. 279,687.

To all whom it may concern:

Be it known that we, ALBERT HENRY and GILBERT V. B. FRICKE, citizens of the United States, and residing at Hoboken, in the county of Hudson and State of New Jersey, have invented certain new and useful Improvements in Shoe-Protectors, of which the following is a specification, such as will enable those skilled in the art to which it appertains to make and use the same.

This invention relates to what are known as shoe protectors, and the object thereof is to provide an improved device of this class which is made in approximate form of an overshoe and which is designed for use by those who operate or work in mines, rolling mills, steel mills and other places of the same or other class for the purpose of protecting the ordinary shoes worn by workmen in places of this class; and with this and other objects in view the invention consists of a device of the class specified, constructed as hereinafter described and claimed.

The invention is fully disclosed in the following specification, of which the accompanying drawing forms a part, in which the separate parts of our improvement are designated by suitable reference characters in each of the views, and in which:

Figure 1 is a plan view of a shoe protector made in the general form of an overshoe and involving our invention;

Fig. 2 a side view thereof with part of the construction broken away;

Fig. 3 a bottom plan view; and,

Fig. 4 a section on the line 4—4 of Fig. 3.

For the purpose of this description we will call our invention a protector shoe, and our improved protector shoe is composed of sheet steel or other sheet metal and comprises a back part 5 and a front part 6, said parts being open at the top and being similar in form, when connected to a low-cut overshoe. The parts 5 and 6 are connected at 7 where they are hinged together, the hinge in the construction shown being composed of parts of the material of the bottom of the device, and a pin 8 which is passed through sleeve members formed from said parts in the usual manner.

The sides 9 of the front part 6 overlap the sides 10 of the back or rear part 5, as shown at 11, and said parts, and particularly the front part, are adapted to swing on the

hinge at 7 so as to permit of the free use of the device in walking and the overlapping side members at 11 are preferably provided one with a curved groove 12 and the other with a corresponding bead 13 which fits 60 therein.

It will be understood that the protector shoe, or the parts 5 and 6 thereof are formed by stamping or fashioning the sheet metal into the desired shape, and in this 65 operation the soles or bottoms of the parts 5 and 6 are formed with or provided with, projecting knobs or conical members 14 which are designed, in the usual manner, to prevent slipping.

The heel or back portion 5 of the protector shoe is provided with a raised member 15 which may be connected therewith in any desired manner, and which extends entirely around said heel portion, and which 70 is composed of a suitable wire mesh, and the side parts of which are provided with recesses or depressions 16 to accommodate the ankle bones of the wearer, and one of 75 said side portions is provided at its front 80 edge with a wire mesh strap 17 which is secured thereto by riveting or otherwise as shown at 18, and the free end of said wire mesh strap is adapted to be passed through a loop or other keeper 19 and to be folded 85 back and secured to the body portion of said strap at 20 by means of ball and socket fastening devices 21 and 22 so as to secure the front of the sides of the part 15 around the ankle or over the instep.

The front part of the protector shoe is also provided with a suitable wire mesh strap 23 which is secured to one side portion thereof at 24 by riveting or otherwise, and the opposite side portion is provided 90 with a keeper 25 through which the free end of the strap 23 is passed, and in the use of this device said strap is passed through said keeper and folded back over the foot and the free end of said strap is connected with 100 the body portion thereof at 26 by ball and socket fastening devices 27 and 28.

The heel and toe portions of the protector shoe are also provided with keepers or similar devices 29 and 30, and when the protector shoe is not in use, the toe portion may be folded backwardly as indicated in dotted lines in Fig. 2, and connected with the heel portion by a chain or any other suitable device 31, which also may be used for suspend- 110

ing the protector shoe from the belt of the workmen or wearer.

The use of this protector shoe will, of course, be similar to that of an ordinary overshoe and in use shoes of this class will protect ordinary shoes made of leather, canvas or other material from injury by acids or other liquids coming in contact therewith, and from heat or heated particles of metal or other material when the protector shoe or shoes are used by miners, metal workers or other operatives.

While we have shown and described what appears to us to be the best method of constructing our invention, it will be understood that the invention is not limited to the details thereof herein shown and described, and changes therein and modifications thereof may be made, within the scope of the appended claims, without departing from the spirit of our invention or sacrificing its advantages.

Having fully described our invention, what we claim as new and desire to secure by Letters Patent, is:—

1. A protector shoe of the class described comprising a toe part and a heel part, said toe and heel parts being movably connected to permit of the folding of one of said parts upon the other, said parts being each provided with raised sides which extend around each of said parts and the sides of said parts being overlapped and interlocked where the separate parts of the shoe are movably connected.

2. A protector shoe of the class described comprising a toe part and a heel part, said

toe and heel parts being composed of sheet metal and movably connected to permit of the folding of one of said parts upon the other, said parts being each provided with raised sides which extend around each of said parts, the sides of said parts being overlapped and interlocked where the separate parts of the shoe are movably connected, and the heel part being provided with a raised wire mesh ankle portion fashioned to conform with the ankle and secured to the top of the heel part.

3. A protector shoe of the class described comprising a toe part and a heel part, said toe and heel parts being composed of sheet metal and movably connected to permit of the folding of one of said parts upon the other, said parts being each provided with raised sides which extend around each of said parts, the sides of said parts being overlapped and interlocked where the separate parts of the shoe are movably connected, the heel part being provided with a raised wire mesh ankle portion fashioned to conform with the ankle and secured to the top of the heel part, and wire mesh straps for securing the toe and heel parts to the foot of the wearer.

In testimony that we claim the foregoing as our invention we have signed our names in presence of the subscribing witnesses this 26th day of February 1919.

ALBERT HENRY.

GILBERT V. B. FRICKE.
